UNITED STATES PATENT OFFICE.

JOHN FLETCHER GRIMMETT, OF BOISSEVAIN, CANADA.

SWINGING CRADLE.

SPECIFICATION forming part of Letters Patent No. 643,267, dated February 13, 1900.

Application filed June 28, 1899. Serial No. 722,168. (No model.)

To all whom it may concern:

Be it known that I, JOHN FLETCHER GRIMMETT, a subject of Her Majesty the Queen of Great Britain, residing at Boissevain, county 5 of Turtle Mountain, Province of Manitoba, Canada, have invented certain new and useful Improvements in Swinging Cradles; and I do hereby declare that the following is a full, clear, and exact description of the invention, such as will enable others skilled in the art to which it appertains to make and use the same.

This invention relates to swinging cradles, and has for one object to provide a swinging cradle which is operated by a clock mechanism.

A further object is to provide a swinging cradle which can be operated without attention for any predetermined length of time and 20 which is simple in construction, effective in operation, and which can be manufactured at a low cost.

To these ends the invention consists in a swinging cradle constructed and operated substantially as hereinafter illustrated and 25 described, and defined in the appended claims.

Referring to the drawings, in which similar letters of reference indicate similar parts, 30 Figure 1 is a side view of the invention. Fig. 2 is a view in perspective of a detail of the construction.

In the drawings, A represents the frame which supports the cradle B and comprises 35 two standards a and a' and a connecting-bar a^2 . Suitable strengthening-braces a^3 are arranged on each side of the standards to give the requisite rigidity to the frame. The upper ends of the standards a and a' are bent 40 transversely and then downwardly, forming a bracket a^4 , which is perforated to receive a bolt b' , which serve as pivotal supports for the arms b of the cradle B. These arms B^6 are securely bolted to the head and foot of 45 the cradle and extend upwardly, the upper extremities of which are preferably curved so as to extend over the bracket a^4 . The pivot-bolts b' pass through the curved end of the supporting-arms b and through the perforations in the brackets a^4 , and thus permit the 50 free swinging or oscillating movement of the cradle. Upon the standards a is fixed a clock

mechanism C of any ordinary or preferred form, the main spindle C' of which terminates in a crank-lever C², which is arranged so as 55 to engage the inner sides of two segments D D', secured to a plate E, fixed to the cradle-arm b . The segments D D' are provided with a curved end portion, which are oppositely arranged, so that, as shown in Fig. 2, the inner sides form a recess or opening of substantially oval shape, in which the crank-lever C² works. These segments are secured to the plate E by means of threaded bolts passing through the straight portion of the said segments, and 60 the said bolts extend through transverse slots formed in the plate E and are provided upon their inner ends with binding-nuts by means of which the said bolts may be fixed in their adjusted position. By means of this construction the segments D D' are capable of being 65 adjusted so as to vary the size of the opening between them. The inner faces of the segments and also the crank-lever may be covered with rubber or other suitable material 70 to serve as a cushion, if so desired. The clock mechanism may be so set as to operate the cradle for any desired length of time. This mechanism is as well adapted for use with 75 toy cradles for dolls as those of larger make, 80 it being only necessary to vary the power of the clock mechanism.

While I have herein shown a preferred form of carrying my invention into effect, yet I do not desire to limit myself to such preferred details of construction, but claim the right to use any and all modifications thereof which will serve to carry into effect the objects to be attained by this invention in so far as such modifications and changes may 85 fall within the spirit and scope of my said invention.

I claim—

1. In a swinging cradle, the combination with a frame, of a cradle pivoted to swing in 95 said frame, a clock mechanism mounted on said frame, a crank-lever fixed on the end of the main spindle of said clock mechanism, a plate fixed upon said frame and segments adjustably secured to said plate and adapted to 100 be engaged by said lever, whereby the cradle is operated, substantially as described.

2. In a swinging cradle, the combination with a frame, of a cradle pivoted to swing in

said frame, a clock mechanism mounted on said frame, a crank-lever fixed on said frame, a plate secured to said frame, and horizontally-arranged segments adjustably mounted upon said plate, each of said segments having a hook end adapted to be engaged by said crank-lever, and a plane working surface terminating in a curve upon which the end of

the said lever is adapted to travel, substantially as described. 10

In witness whereof I have hereunto set my hand in the presence of two witnesses.

JOHN FLETCHER GRIMMETT.
